UNITED STATES PATENT OFFICE.

JOHN WILLIAM GODDARD AND ARTHUR ERNEST JERRAM, OF LEICESTER, ENGLAND,
ASSIGNORS, BY MESNE ASSIGNMENTS, TO UNITED SHOE MACHINERY CORPORATION, OF PATERSON, NEW JERSEY, A CORPORATION OF NEW JERSEY.

SOLE-SEWING MACHINE.

1,353,827.

Specification of Letters Patent. Patented Sept. 28, 1920.

Application filed February 21, 1917. Serial No. 150,190.

To all whom it may concern:

Be it known that we, JOHN W. GODDARD and ARTHUR E. JERRAM, subjects of the King of Great Britain, residing at Leicester, in the county of Leicester, England, have invented certain new and useful Improvements in Sole-Sewing Machines; and we do hereby declare the following to be a full, clear, and exact description of the invention, such as will enable others skilled in the art to which it appertains to make and use the same.

The present invention relates to sole sewing machines, and more particularly to machines of the type having a rotatable horn upon which the work is supported, and which carries a looper for placing the thread in the barb of the needle, which latter penetrates the work from the side opposite to that side of the work which is on the horn.

An object of the invention is to provide certain improvements in that class of machines of the above kind which act to form a lockstitch, the loop of thread drawn through the work by the needle being passed around a shuttle which is given a rotary movement preferably continuously in the same direction. In some of these machines the loop of thread for the needle is supplied in part by the drawing down to the work of a slack loop left standing from the previous stitch and in part from the thread supply means (including a take-up at the base of the horn), and the shuttle by drawing taut the needle loop completes the setting of the last stitch and draws off from the needle thread supply a sufficient quantity for the stitch, the loop escaping from around the shuttle being then partly drawn through the work by the takeup. Customarily the shuttle is moved to rotate about a more or less horizontal axis which usually runs from front to back of the machine, and usually there is a more or less

vertical main shaft having cam or other devices at its lower part to operate the looper and takeup, and at its upper end a hand wheel for turning the machine by hand, together with an assemblage of cams (either actually on the main shaft or upon a cross shaft) for operating various of the operative members such as the needle bar, the feed point, the presser foot, and the shuttle. An example of this class of machine to which

the invention in certain of its aspects more particularly relates is disclosed in the patent to John W. Goddard, No. 1,171,714, dated February 15, 1916.

The chief purpose of the improvements according to the invention is to permit of increase in the speed of operation of such machines and of reduction of the time occupied in inevitable stoppages in the operation of the machine, with a view to increasing the output capacity of such machines.

One object of the invention is to facilitate the placing of work upon and the withdrawal of the same from the work supporting horn of sole sewing machines. With this object in view, one feature of the invention consists of, in a sole sewing machine, a construction of the looper actuating mechanism and the horn such that the tip of the latter can be moved laterally out of and into sewing position without producing such disconnection of the actuating mechanism as permits variation of the timing of the looper.

Conveniently, there is provided a device controlling the position of the horn, which device may be coupled to the presser foot, and connections between the device and the machine starting treadle such as to prevent starting of the machine until the horn is either fully out of or in sewing position.

Another object of the invention is to facilitate access to the bobbin and to the operative mechanism in the neighborhood thereof in lockstitch sole sewing machines which have a deflecting element which acts to deflect or spread the loop to enable it more readily to be taken by the shuttle (see for example the machine of Patent No. 1,171,714) and according to another feature of the invention this is effected by mounting the deflecting element upon the bobbin cover so as to move out of position with the cover.

A further object is to provide for a shuttle in a lockstitch sole sewing machine in which the shuttle is given both a rotary movement for passing the loop around the shuttle and an axial movement so as to approach the shuttle to and retract it from the path of the needle, a construction of driving mechanism particularly adapted for running the shuttle at high speeds and for obtaining certain control of the shuttle throughout its movements.

According to this feature of the invention the shuttle is mounted for rotary movement in a member which reciprocates transversely of the plane of the aforesaid movement, and 5 the shuttle has its rotary movement imparted to it by drivers adapted to move into and out of engagement with the shuttle and guided in a member which is given a rotary movement to move the shuttle, but is 10 held against movement transversely of the said plane. Preferably the member moves in the vicinity of stationary cams means which act to effect the advance and withdrawal of the drivers.

15 A further object of the invention is to provide improved work feed mechanism for sole sewing machines. Customarily in sole sewing machines the presser foot acts as a support for the feed point, and when the 20 presser foot is lifted in preparation for the feed movement, the feed point is in consequence slightly lifted. At this time, therefore, not only is work released by the presser foot, but the feed point to some extent releases its hold upon the work, and the accuracy of feed and of positioning of the work may be materially affected, especially 25 when the work is held much inclined to the horizontal. Again the fact that the feed 30 point in such machines enters the work in an inclined direction, and drags back over the work on the return stroke, has been found to have disadvantages which it is an object of the present invention to overcome.

35 With these further objects in view, one feature of the present invention consists of, in a sole sewing machine, the combination of a needle bar actuated to move toward and from the work in the same path, work clamping 40 means (for instance a co-acting presser foot and horn) and a feed member (laterally movable to feed the work) which moves toward the work along a pathway substantially perpendicular to the same, and is 45 operated during sewing to be in effective control of the work at all such times as the clamping means ceases to have such control.

50 A further feature of the invention is, in a sole sewing machine, the combination of work clamping means (for instance a co-acting presser foot and horn) and a feed member movable into and out of controlling engagement with the work, with actuating 55 means therefor constructed and arranged so that in the sewing operation the coming into controlling engagement of the feed member with the work allows of separation of the clamping means to release the work 60 and vice versa. A convenient construction, according to this feature of the invention, comprises a support for a clamping member, a support for the feed member, and an operative connection between these parts 65 such that actuation of the said connection

first brings one of these members into controlling engagement with the work, and then using such member as an abutment, withdraws the other member from such engagement.

70

Another feature of the invention is, in a sole sewing machine, a presser foot movably mounted upon its support in such a manner that while the raising of the support relieves the work of the normal pressure of the 75 presser foot, the presser foot actually remains lightly in contact with the work to act as a guide in channeled work.

These and other objects and features of the present invention will be evident from 80 the following description, by way of example, of a sewing machine according to the invention.

This machine is a lockstitch sole sewer of the general character of that described in 85 patent No. 1,171,714. It has a whirl and a loop-positioning device constructed and arranged in the manner described in said patent. In addition it has needle bar operating mechanism of the character disclosed in 90 the patent to Arthur E. Jerram, No. 1,120,201, dated December 8, 1914.

In the accompanying drawings, Figure 1 is a general side elevation of the machine; Fig. 2 is a detailed view in side elevation and 95 partly in section of the base of the machine; Fig. 3 is a similar view of the head of the machine; Fig. 4 is a detailed view in side elevation and in section of the devices for driving the shuttle; Fig. 5 is a view in 100 front elevation and in part section of the head of the machine; Fig. 6 is a horizontal section of the presser foot and feed point supports; and Fig. 7 is a diagram of the 105 cycle of operations of various of the elements of the machine.

In some of the views certain parts have been omitted for the sake of simplicity.

Like reference characters indicate like parts in all the figures.

110

In the base of the machine and running from back to front is a driving shaft 1 (Fig. 2) connected by a clutch (not shown) at the rear of the machine to the source of power and carrying near its forward end a bevel gear wheel 2 meshing with a similar gear wheel 3 on the bottom end of a more or less upright shaft 4 running up inside the standard 5 of the machine and projecting from the same at the top of the machine as shown 115 in Fig. 3.

This shaft carries toward its lower end a barrel member 6 in which are formed three cam tracks 7, 8, 9, one for operating the thread lock (to be hereinafter described), and the others for operating the levers of the takeup device, which will be described below. Adjacent to this member is a bevel gear wheel 10 meshing with a 120 similar gear wheel 11 of the mechanism for 125 130

driving the whirl in the horn. At its uppermost extremity the shaft bears a hand wheel 12 by which the machine can be slowly turned by hand and immediately beneath this hand wheel and within the standard the shaft carries a bevel gear wheel 13 for operating the main shaft on the machine head, and an eccentric 14 for reciprocating the shuttle carrier axially, and is in 10 driving connection by means of spiral gears 200, 201 with a more or less horizontal rotatable shaft 15 which operates the shuttle drivers.

The horn 16 (Figs. 1 and 2), which is of a long pattern suited to long boot work, carries at its upper end the customary whirl. The whirl is driven by the usual bevel gear wheels on the ends of shafts located in the horn, the bottom bevel gear wheel meshing 20 with a gear wheel on the upper end of a vertical tubular shaft having bearings in the base of the horn, and provided at the lower end with a bevel gear wheel 17 (Fig. 2) meshing with a similar gear wheel 18 on one 25 end of a short horizontal shaft 19, on the other end of which is the gear wheel 11 above referred to as meshing with a corresponding bevel gear wheel 10 on the upright shaft 4 in the machine standard.

30 The horn is mounted to be free to rotate on a ball race carried in a horn support 20 having depending lugs 21 at opposite sides in which are bearings for short coaxial shafts 22 projecting from opposite sides of 35 the machine frame below the horn and running from side to side of the machine. The horn can thus be swung forwardly toward the operator out of its normal upright position, giving increased clearance between the 40 tip of the horn and the various devices of the head, such as the presser foot, feed point and needle, and facilitating the rapid withdrawal of the work from and placing of work upon the horn.

45 The axis of the shafts about which the horn swings is so disposed as to be tangential to the bevel gear wheels 17 and 18, on the tubular shaft and the horizontal driving shaft 19 respectively, at the point 23 where 50 their bases mesh, and a stop 24 on the machine frame is adapted to form an abutment for the horn support when the latter is swung fully out. This arrangement secures that the horn may be free to swing and the 55 gear wheel 17 may be free to swing away from the gear wheel 18 without at the same time these gear wheels becoming completely unmeshed, and any risk of change of timing of the whirl arising.

60 Mounted to be movable horizontally from back to front of the machine is a locking bolt 25 having a wedge shaped forward portion 26 adapted to engage over a wedge shaped projection 27 on one side of the horn 65 support when the horn is upright, and to

lock it in position, or to engage beneath the projection when the horn has been swung out of position and so hold it in that position. The bolt 25 is engaged by one end of a lever 28 by which it is moved horizontally 70 to and fro to effect locking and unlocking of the horn. This lever is pivoted at 29 inside the standard of the machine, and carries at its other end a roll 30 engaging a cam track 31 formed at one end of an arm 75 32 of a bell crank lever pivoted at 33 on the standard the other end of the second arm of which is pivotally connected at 34 to the upper end of an operating rod 35 herein-after referred to. The cam track 31 is also 80 engaged by a roll 360 mounted on one arm of another bell-crank lever 370 pivoted on the standard at 380 the other arm of which is connected, by a rod 390, extending up the standard to the head of the machine, to the 85 presser foot lifting lever. The arrangement of the bell-crank levers and the lever 28 connected to the bolt 25 as well as the form of the cam track 31 is such that if the arm 32 carrying the cam track is swung under the influence of the operating rod 35 in one direction the presser foot is first raised and as the arm swings further the locking bolt is withdrawn and the horn can be swung out of position. Conversely upon movement of the arm in the other direction the bolt is 90 first advanced to lock the horn in the in or out position as the case may be and then the presser foot is allowed to descend. There is provided in conjunction with the operating rod 35 mechanism which aims at insuring that the clutch shall not be thrown in except when the presser foot is down (and the horn consequently locked in the in or out positions) and that danger of the machine being started with the horn in an intermediate position, involving possible damage to the needle and associated parts, shall be avoided.

95 The clutch-operating lever 36 extends 110 toward the front of the machine and has projecting from one side of it a horizontal pin 37 with a V-notch cut in its upper side. Pivoted on the same shaft 38 as the clutch-operating lever 36 is a second lever 39 lying 115 alongside the latter and having projecting from it adjacent to the clutch-operating lever a pin 40 similar to that already referred to but situated a little farther from the shaft 38 upon which the levers are mounted. The 120 lever 39 is normally held up by a spring 41 against a stop 42 on the machine base and is pivotally connected at 43 to the lower end of the operating rod 35. A treadle 44 for operating both the clutch and the presser 125 foot and horn lock is also mounted upon the shaft 38 and is normally urged upward by a spring 45 connected at one end to the lever and at the other end to the machine frame. In the neighborhood of the horizontal pins 130

37, 40 the treadle 44 has an upstanding bracket 46 from which a short horizontal shaft 47 projects over the pins referred to. An arm 48 is mounted on this shaft so as to be capable of swinging over either of the pins 37, 40 and engaging in the V-notch of one or other of them when the treadle 44 is depressed. On the end of the treadle on which the operator places his foot is an upstanding arch or stirrup 49 from which depends a plate 50 which the operator can thrust forward by forward motion of his foot on the treadle and a rod 51 is disposed between and connects this plate with the arm 48 so that the operator can swing the latter into position over the notch in the pin 37 on the clutch-operating lever 36. A spring-pressed plunger 52 housed in the upstanding bracket 46 bears on the opposite side of the arm 48 and acts normally to maintain the arm in position over the notch in the pin 40 on the lever 39.

When once the presser foot has been raised and the horn swung out of position 25 the pivotal arm 48 on the treadle 44 will remain in engagement with the notched pin 40 on the lever 39 until such time when on the treadle 44 rising the lever 39 is urged by its spring 41 against the stop 42 and there 30 arrested when further upward movement of the treadle will bring the arm 48 out of the notch in the pin 40 and leave it free (the presser foot being now in normal depressed position and the horn locked in the in or out 35 position) to be swung over to engage the pin 37 on the clutch-operating lever 36 and allow the clutch to be thrown in.

In a chamber formed in the frame of the machine below the horn support are the 40 thread-locking and thread take-up devices. The thread-locking device comprises a lever 53, pivoted on the frame at 54, one arm of which is hollowed to receive a spring-pressed plunger 55 which when the lever is 45 swung in one direction is brought against a surface 56 on a fixed arm 57 projecting from the frame. The surface 56 and the plunger 55 are grooved transversely to the direction of the thread, which passes therebetween, so 50 as to afford a good grip on the thread. The other arm of the lever 53 is connected to the frame of the machine by a light spring 58 which normally urges the plunger 55 against the surface 56. The plunger being yield- 55 ingly forced against the surface, variation in thread substance can take place without any tendency to cut or crush the thread unduly during the locking. The other arm of the lever 53 is also adapted to be engaged by 60 one arm of a tappet lever 59 pivoted on the frame the end of the other arm of which is formed as a cylindrical pin 60 engaging and capable of moving longitudinally in a ball 61 engaged in the corresponding cam track 65 9 of the barrel member 6 on the upright

driving shaft 4 in the standard of the machine. In cross section the cam track is circular and the ball is thus held firmly in the track, there being a cutaway portion (conforming to the cam track) a little wider 70 than the diameter of the pin 60 through which the latter projects.

The fixed arm 57 which carries one of the thread-engaging surfaces also carries a pulley around which the thread passes as it 75 leaves the locking device. From this pulley the thread passes upward over a pulley 62 on the upper of two take-up levers 63, 64 and thence down and around a pulley 65 on the lower of the take-up levers the thread 80 then passing vertically upward into the tubular shaft in the base of the horn. The take-up levers are each pivoted to the frame of the machine and their ends remote from those carrying the pulleys engage in balls in 85 the cam tracks 7, 8 on the barrel member 6 in the same way as the operating lever for the lock already described. The cam tracks are so formed that the take-up levers have a scissor-like movement both moving together 90 or apart at the same time.

The shuttle 66 (Fig. 4) is mounted to rotate on an axis running from the front to the back of the machine and slightly inclined to the horizontal so that the body portion 95 of the shuttle is clear of the needle bar when the beak 67 of the shuttle is taking the loop of thread. A shuttle-carrying casing 68 is provided which is pinned to one end of a shaft 69 parallel to but above the axis of 100 rotation of the shuttle. The shaft 69 has bearings in the head of the machine and is free to move longitudinally in its bearings. Its other end is connected by an eccentric adjusting pin 70 (Fig. 3) to an eccentric arm 71 the strap 72 of which encircles the eccentric 14 (already referred to) on the upright shaft 4 in the machine standard. The casing and the shuttle carried by it are by this mechanism reciprocated axially into and out of the path of the needle once in every revolution of the upright shaft 4. The casing has two curved plates 73, 74 (Fig. 4) removably mounted on it which together form a part circular 115 flange which projects into a peripheral recess 75 in the shuttle and thus forms the support and bearing surface for the shuttle in its rotary and axial movements.

To rotate the shuttle the shaft 15, hereinbefore referred to, is provided which is coaxial with the axis of rotation of the shuttle. The driving connection between the shaft 15 and the upright shaft 4 causes the shaft 15 to perform two complete revolutions for every revolution of the shaft 4, and thus, as will be hereinafter explained, for every complete cycle of operations of the needle and associated members. Pinned to the forward end of the shaft 15 is a cy- 120 125 130

cylindrical block 76 having two diametrically opposite grooves cut on its outside face parallel to the axis of the shaft. In each groove is mounted a shuttle driver 77 the 5 forward end of which can be reciprocated into and out of a corresponding recess in the rear face of the shuttle the reciprocation of the drivers being effected on the rotation of the block 76 by the coaction of a pin 78 10 projecting from each driver with the corresponding one of two cam tracks 79, 80 formed on the inside walls of a fixed cup 81 within which the block 76 rotates.

The shuttle-carrying casing 68 is provided with a hinged cover 82 mounted and actuated in the same manner as the bobbin holding arm disclosed in Patent No. 1,171,714, except that the axis of the hinge is horizontal so that the cover swings forward and upwardly on opening. A loop deflector of the kind disclosed in Patent No. 1,171,714 is mounted on this cover so that it is swung out of the way when the cover is swung open. The deflector consists of a 25 vertically disposed lever 83 (Fig. 5) pivoted by a pin 84 mounted in the shuttle cover so as to swing on an axis running from side to side of the machine and so that the lower end of the lever can swing across the path 30 of the needle toward the shuttle when its upper end is engaged by a cam piece 85 on the needle bar 86, there being a spring 87 coiled about the pivot with which the lever 83 swings which acts normally to keep the 35 lower end of the lever to that side of the path of the needle remote from the shuttle.

The needle bar 86 is mounted to slide in top and bottom bearings 88, 89 in the front of the machine head and between these 40 bearings has a block 90 attached to it, which block is in engagement with a vertical guide-way 91 on the head and holds the needle bar against rotation. Pivoted to this block is one end of a link 92 the other end of 45 which is pivotally connected to one arm 93 of a bell-crank lever pivoted on a crank 94 on the main shaft on the machine head. The other arm 95 (see also Fig. 3) of the bell-crank lever carries a roll 96 engaging a cam 50 track 97 formed in the side of a fixed cam disk 98 disposed coaxially with the main shaft 99 on the machine head. The link 92, bell-crank lever 93-95, crank 94 and cam track 97 are so formed and arranged that 55 the needle bar is operated in the manner indicated in the specification of Letters Patent No. 1,120,201.

Fast to the main shaft on the head is a cam disk 100 (Fig. 3) having, for the purposes hereinafter described, formed on one 60 face of it two cam tracks 101, 102 and having a single cam track 103 on the other face. The presser foot 101 (Fig. 5) is pivotally mounted at the bottom of the presser foot 65 bar 105 and is urged normally against a stop

106 by a spring-pressed plunger 107 mounted in the presser foot and bearing on the presser foot bar, the arrangement being such that when the presser foot is clamping the work this plunger has been thrust back and the presser foot is in direct and unyielding contact with the presser foot bar whereas the spring-pressed plunger becomes effective during the feeding movements to swing the work-engaging surface of the presser foot 70 down and maintain it under light spring pressure in the channel or groove, if any, along which the line of stitching is to be laid. The presser foot bar 105 is provided with a longitudinal (*i. e.* vertical) guide or 75 recess adapted to receive the feed point bar 108 (see also Fig. 6) and guide it in its vertical movements while allowing a limited movement of the feed point bar 108 laterally away from the presser foot bar 105. The 80 tops of the presser foot bar 105 and of the feed point bar 108 are respectively pivoted at 109, 110 to the two bottom corners of a vertically disposed triangular plate 111 the 85 upper corner 112 of which is pivotally connected by a link 113 to one arm 114 of a bell-crank lever pivoted at 115 to the machine head the other arm 116 of which carries a roll 117 (Fig. 3) engaging the cam track 103 in the cam disk 100. The arrangement is such that the link 113 in the alternate raising and lowering of the presser foot and feed point reciprocates the triangular plate 111 the point of connection of 90 one of the bars (*i. e.* presser foot bar 105 or feed point bar 108) to the plate 111 and then the other forming the fulcrum about which the plate moves, the point of connection about which the plate is swung at any particular time being stationary by virtue of 95 the fact that the bar which carries it is at that time bearing on the work. In other words while the plate 111 is swinging to raise the presser foot the point of connection 100 110 of the feed point bar (the feed point at that time engaging the work) to the plate 111 forms the fulcrum of the plate and vice versa.

As a result of this arrangement at any time either the feed point or the presser foot is in engagement with and duly positioning the work. To urge the triangular plate 111 and the feed point and presser foot toward the work with the requisite pressure a spiral spring 118 is provided 115 which bears at the bottom end on a collar 119 formed at the bottom end of a pin 120 (around which the spring is coiled) the bottom end of which rests in a cavity formed in the top of the triangular plate the top 120 end of the pin being free to slide in a bearing 121 which is mounted to swivel in the machine head (as the pin swivels during reciprocation of the triangular plate) and against which the top end of the spring 125 130

bears. The feed point bar 108 is swung about its point of connection to the triangular plate 111 to give the necessary feeding motion to the feed point by a bell-crank lever pivoted on the machine head and bearing on one arm 122 a roll which engages the cam track 101 on the cam disk 100 and on the other arm 123 a pin 124 connects that arm to the lower end of the feed point bar 108. Both the feed point bar 108 and the arm 123 are slotted so that the pin 124 may be moved along the slots to adjust the feed stroke the pin being provided with a clamping nut 125 to secure it in adjusted position 15 in the slots.

The link 113 which operates the triangular plate 111 is provided with a projecting tail 126 against which the end of a lever 127 pivoted on the machine head at 128 and running horizontally from front to back thereof can engage to lift the presser foot from the work, this presser foot lifting lever being, as already referred to, connected to the operating rod 390 which extends up the standard of the machine.

To lock the presser foot in position a bell-crank lever is mounted on one side of the machine head one arm 129 of which lever has a wedge-shaped end portion adapted to be forced against the presser foot bar to lock it by a spring-pressed plunger 132 which is housed in the machine head and urges the wedge surface on the arm 129 normally into contact with the side of the presser foot bar 105. To unlock the presser foot bar at the required times a tappet lever 130 is provided bearing on the other arm 131 of the bell-crank lever and operated by the cam track 102 on the cam disk 100 to remove the wedge surface out of contact with the presser foot bar.

The operation of the machine is as follows:—

Assuming the horn 16 to have been swung in its outward position the operator first places the work upon the horn and then depresses the treadle 44 thus raising the presser foot and drawing back the locking bolt 25. The horn is now free to be moved into the upright position and the operator having so moved it he releases the treadle allowing the presser foot to fall and the bolt 25 to advance to lock the horn in position. The treadle having risen sufficiently to clear the arm 48 from the notched pin 40 on the lever 39 the operator thrusts his foot against the plate 50 and thereby swings the arm 48 over the notched pin 37 on the clutch-operating lever 36 and on then depressing the treadle 60 the clutch is thrown in and sewing commences.

It will be convenient to commence the consideration of the sewing operation at the moment when the needle is about to move down toward the work from its highest

point (see curve A, B, Fig. 7). At this time the shuttle 66 has very nearly completed its axial movement in the direction toward the path of the needle (see curve C, D, Fig. 7) and the beak 67 of the shuttle is almost 70 in the loop-receiving position. At this time the presser foot support 105 is held raised (see curve E, F, Fig. 7) in anticipation of the feed movement of the work now about to commence while the loop deflector 83 75 (see curve G, H, Fig. 7) is in its inmost position to bear on the loop between the needle and the surface of the work.

At the moment the needle commences to descend the beak 67 of the shuttle has penetrated well into the loop and the feed point (see curve L, M, Fig. 7) commences its horizontal feeding movement. Meanwhile the take-up levers 63, 64 (see curves N, O and P, Q, Fig. 7) are advancing toward each other to give off thread to meet the demands of the loop as the beak 67 advances through the same. The needle descending farther the beak advances until the loop rests in the bottom of the recess behind the beak this 90 occurring practically at the time when the shuttle has advanced in its forward limit of axial movement. At this moment the loop has passed off the needle and the loop of the needle thread of the last stitch having 95 by the advance of the beak through the loop on the needle been drawn down and into the work to complete the setting of the last stitch the thread lock 55, 56 (see curve R, S, Fig. 7) is unlocked so that on the continued 100 rotation of the shuttle and continued approach of the take-up levers any excess of thread required over that supplied by the take-up can be drawn off through the tension device of the machine. At this time 105 moreover the loop deflector 83 which has been gradually moving away from the needle path (see curve G, H) and out of loop-deflecting position completes this movement. Shortly before the bottom of 110 the recess behind the beak 67 reaches, in the rotation of the shuttle, its highest point (the movements of the bottom of the recess being shown in the curve T, U, Fig. 7) the feed movement of the feed point is completed 115 (see curve L, M) and almost immediately afterward the presser foot support 105 (see curve E, F) commences to descend toward the work. Very shortly after the bottom of 120 the recess referred to has passed its highest point (see curve T, U) the thread lock 55, 56 (see curve R, S) once more comes into operation to lock the thread and then, the presser foot having come fully down upon the work (see curve E, F), the feed point 125 commences to lift away from the work (see curve X, Y, Fig. 7) and simultaneously to return horizontally to starting position (see curve L, M) so that in effect it commences to leave the work in an inclined direction. 130

The bottom of the recess behind the shuttle beak having now traveled well past its highest point (see curve T, U) the take-up levers commence to move away from each other

- 5 to draw the loop off the shuttle and toward the work (see curves N, O and P, Q). Just before the needle penetrates the work (see curve A, B) as the result of its continued downward movement the locking device 10 129, 132 for the presser foot support (see curve W, V, Fig. 7) comes into operation to lock the same in its lowermost position in contact with the work. Shortly afterward, having completed its horizontal return 15 movement toward the starting position, the feed point begins to descend vertically (see curve X, Y) toward and into engagement with the work which movement it completes at about the time when the needle (see curve 20 A, B) leaves the work on the underside to penetrate into the horn and when the shuttle has completed about three-quarters of its rearward axial movement (see curve C, D) away from the path of the needle. At this 25 time the shuttle has nearly completed a revolution (see curve T, U) and the take-up levers (see curves N, O and P, Q) have come to a stop at their widest separation having taken up all but a small loop of thread 30 which remains upstanding above the work.

Shortly after the bottom of the recess behind the beak (see curve T, U) has once more passed its highest point (the shuttle being then in the course of gradually ad-

- 35 vancing axially toward the needle path as shown by curve C, D) the needle, which has for some time been stationary (see curve A, B) in its lowest position to allow of the placing of the thread in its barb by the 40 looper, commences to rise drawing up a loop of thread one leg of which is supplied from the take-up levers which now commence their movement of relative approach (see curves N, O and P, Q) and the other 45 leg of which is supplied by the upstanding loop in the last stitch which as the needle rises is gradually drawn down to the surface of the work. As the needle in its upward movement leaves the work the presser 50 bar support 105 is unlocked (see curve W, V) and as the needle completes its upward movement the presser foot commences to lift (see curve E, F) in anticipation of the next feed movement and the loop deflector 55 begins to swing toward the loop (see curve G, H) to deflect it in a direction to aid the entry of the beak 67 which is now once again nearly in loop-receiving position.

The nature and scope of the invention 60 having been indicated and a machine embodying the several features of the invention in their preferred form having been specifically described, what is claimed is:

1. A sole sewing machine, having in combination, a straight barbed needle, a shoe

supporting horn mounted to permit a lateral movement of the horn tip out of and into sewing position, and a looper located in the horn.

2. A sole sewing machine, having in combination, a straight barbed needle, a shoe supporting horn mounted to permit a lateral movement of the horn tip out of and into sewing position, a looper located in the horn, and mechanism for actuating the looper and 70 maintaining its timed relation to the needle.

3. A sole sewing machine, having in combination, a straight barbed needle, a shoe supporting horn mounted to permit a lateral movement of the horn tip out of and into 75 sewing position, a looper located in the horn, and means to prevent starting the machine into operation during the movement of the horn from one position to the other.

4. A sole sewing machine, having in combination, a straight barbed needle, a shoe supporting horn mounted to permit a lateral movement of the horn tip out of and into sewing position, a looper located in the horn, a lock for the horn, a presser foot, and a 80 connection between the lock and the presser foot.

5. A sole sewing machine having in combination, a straight barbed needle, a rotatable shoe supporting horn, a looper located 95 in the horn, and a base for the horn pivotally mounted to permit a lateral movement of the horn tip out of and into sewing position.

6. A lockstitch sole sewing machine, having in combination, a straight barbed needle, a looper, a shuttle, a bobbin cover movable to expose the bobbin and a loop deflector mounted on the cover.

7. A lockstitch sole sewing machine, having in combination, a straight barbed needle, a looper, a shuttle, a bobbin cover movable to expose the bobbin, a needle bar, a loop deflector mounted on the cover comprising a lever having one end arranged to engage 110 the loop of needle thread, and an actuating cam on the needle bar arranged to engage the other end of the lever.

8. A lockstitch sole sewing machine, having in combination, a straight barbed needle, 115 a looper, a discoidal shuttle, shuttle driving mechanism, a shuttle casing, and means for reciprocating the casing independently of the shuttle driving mechanism to move the shuttle in a substantially axial direction 120 toward and from the needle.

9. A lockstitch sole sewing machine, having in combination, a straight barbed needle, a looper, a discoidal shuttle, shuttle rotating drivers movable into and out of operative 125 engagement with the shuttle, a rotary driver carrier, and means for reciprocating the casing independently of the driver carrier to move the shuttle in a substantially axial direction toward and from the needle.

10. A sole sewing machine, having in combination, a straight barbed needle, a shoe supporting horn, a looper located in the horn, a presser foot, a feed member 5 movable toward and from the work and laterally with relation to the presser foot to feed the work, and means for actuating the presser foot and feed member to control the work alternately and to bring the feed member into control as the presser foot ceases to have control and to maintain one or the other of said members in contact with the work at all times.

11. A sole sewing machine, having in combination, a straight barbed needle, a shoe supporting horn, a looper located in the horn, a presser foot, a feed member, and means for actuating the presser foot and feed member rendered operative to withdraw 20 one of these parts from the work by the engagement of the other part with the work.

12. A sole sewing machine, having in combination, a straight barbed needle, a shoe supporting horn, a looper located in the horn, a presser foot, a carrier therefor, a feeding member, a carrier for said feeding member, and a connection between said carriers acting when actuated to bring the feeding member into controlling engagement

with the work and then using the feeding member as an abutment to withdraw the presser foot from such engagement.

13. A sole sewing machine, having in combination, a straight barbed needle, a shoe supporting horn, a looper located in the horn, a presser foot, a feed member, means for actuating the presser foot and feed member rendered operative to withdraw one of these parts from the work by the engagement of the other part with the work, and means for withdrawing both the presser foot and feed member to permit the removal of work from the machine.

14. A sole sewing machine, having in combination, a straight barbed needle, a shoe supporting horn, a looper located in the horn, a presser foot acting to hold the work while the needle is withdrawing therefrom, a carrier on which the presser foot is yieldingly mounted and means for actuating the presser foot carrier to increase the pressure of the presser foot on the work and bring the foot into unyielding contact with the carrier and to decrease the pressure of the presser foot on the work while permitting the foot to remain in contact with the work.
